[54] REAR DISCHARGE ROTARY LAWN MOWER

Agricultural Machinery Journal Lawn Care Issue, Jan. 1971, p. 9, lawn mower, top left side of page.

[75] Inventors: William A. Cox, Brentwood; Paul L. Scott, Lewisburg; Larry M. Cognata, Nashville, all of Tenn.

Primary Examiner—James M. Gandy
Attorney, Agent, or Firm—John W. Malley

[73] Assignee: The Murray Ohio Manufacturing Co., Brentwood, Tenn.

[57] CLAIM

The ornamental design for a rear discharge rotary lawn mower, substantially as shown and described.

[**] Term: 14 Years

DESCRIPTION

[21] Appl. No.: 896,365

FIG. 1 is a right side elevational view of a rear discharge rotary lawn mower showing our new design;

[22] Filed: Apr. 6, 1978

FIG. 2 is a left side elevational view thereof;

[51] Int. Cl. .... D15—03
[52] U.S. Cl. D15/14
[58] Field of Search D15/14; 56/202, 16.6,
56/13.4

FIG. 3 is a rear elevational view thereof;

FIG. 4 is a right front perspective view thereof;

FIG. 5 is a right front perspective view of a rear discharge rotary lawn mower showing a second embodiment of our new design, it being understood that the only difference resides in the addition of an engine cover; and

FIG. 6 is a left front perspective view of FIG. 5. The broken lines in the drawing are for illustrative purposes only.
